COOLING SYSTEM FOR MARINE AND OTHER ENGINES

Application filed May 25, 1928, Serial No. 280,617, and in Great Britain May 1, 1928.

This invention relates to internal combustion engines and has special reference to a cooling system for internal combustion engines.

5 In the conventional systems wherein the cylinders of the engine are water jacketed and kept from becoming too intensely heated by the circulation of water through the water jacket, the jacket being vented to permit the escape of steam if generated, many objections exist. It is well known that, within proper limits, the greater the temperature of the cylinders the more efficient is the operation of an internal combustion engine. Open, 10 or vented, water cooled systems are therefore objectionable because they keep the cylinder temperature too low when operating as they are intended and permit too great a temperature upon generation of steam. Moreover, it is found that at so low a temperature as 203 15 degrees Fahrenheit (usually much lower) the fluid being circulated becomes uncontrollable by the circulating pump thus making a continuation of operation of the engine 20 under such load as will raise the temperature to 203 degrees Fahrenheit impossible.

The conventional evaporative or steam cooling does, it is true, afford an appreciable increase in economy of fuel and a more flexible motor for automotive work because of increase in jacket temperatures to handle 200 degrees Fahrenheit. The weakness of this system is, however, in its limitation; for it can be shown that atmospheric air is always 25 present and in combination with the steam, produced at 203 degrees and even lower, will prevent the water from making contact with the hottest part of the cylinder head, walls and combustion chamber because the boiling 30 produces insulation of the walls from the liquid by a steam and air film. Indeed at this point spheroidal state of water is reached and the limitation of the system has been reached for cooling except by metallic conductivity of the cylinder walls.

40 With my invention the action of the cooling medium just described is entirely changed. Liquid contact with the hottest part of the cylinder is maintained up to any 45 desired temperature, even to 450 degrees

Fahrenheit or more. The cooling fluid is under perfect control and its velocity, and consequently the volume passing through the jacket in a given time, is increased automatically when additional cooling is required 55 and decreased when the normal requirements are decreased. This is the result sought by the use of my improved hermetically sealed cooling system.

From the above it will be apparent that the vapor pressure on the surface of the liquid acts to maintain the continuity of the column of water between the radiator outlet and the pump and thus insure that the cooling medium is delivered to the pump in mass flow 60 without interruption, the degree of pressure at the pump suction depending upon the vapor pressure. In the absence of vapor pressure, the water is fed to the pump by the hydrostatic head and where the heat of the water at the pump inlet tends to the creation of vapor, and cavitation of the pump takes place, the heat generated by the action of the pump and the suction effect of the pump necessary to draw in the water rapidly 65 creates a steam or vapor condition which eventually breaks down the water column and by the very reason of its production, creates a pressure which acts against the hydrostatic head of the water in the radiator and further 70 tends to prevent the water, except in a very small stream, from reaching the pump. This condition increases for the pump is delivering less and less water to the engine jackets and there is a continually increased heat imparted to the cooling medium. Finally the 75 cavitation effect is such that the pump is receiving no water and the system as a cooling system has broken down. The vapor pressure hereinabove referred to, however, increases with the increased heat of the medium, thereby supplements the hydrostatic head of the water leading to the pump and delivers the water to the pump at a pressure 80 which increases with the increased heat of the cooling medium. Therefore, when the water column between the radiator outlet and the pump is under that degree of heat 85 in the ordinary vented system which would cause the production at the pump inlet of 90

95 100

steam or vapor and thus quickly break down the water column leading to the pump, the vapor pressure in the improved system overcomes this tendency by adding to the hydrostatic head a pressure on the water column leading to the pump which maintains its integrity and insures the delivery of the water in a full mass volume and compels the pump to continually pump water to its full capacity. The vapor pressure then, by maintaining this mass volume delivery to the pump and insuring against the breaking down of the water column, materially assists in the circulation of the water, particularly in its delivery to the pump and this assistance is by pressure and proportional to the heating of the medium in its circulation past the water jacket, it being understood that the pump employed is capable of discharging whatever water it receives against a head pressure greatly in excess of the possible maximum back or discharge pressure attainable in a closed system. It is of course understood that a pump, no matter how great its capacity, is capable of discharging more water than it can receive through its suction inlet. Thus, under full inlet to the pump, the increased flow thereto will be proportional to the increased pressure on the medium delivered to the pump but where the pump inlet is throttled, the increased flow to the pump will not necessarily be proportional to the increased pressure.

If the vapor or gas pressure can be varied, it follows as a matter of course that the flow will be correspondingly varied, such flow being retarded where the vapor or gas pressure is less than atmospheric pressure and increased if the vapor or gas pressure is greater than atmospheric pressure. With the present construction, the pressure at the outlet from the source of supply is the suction draw of the pump plus the hydrostatic head plus the vapor or gas pressure on the surface. With a constant speed of pump, the water is forced into the container, the air expanding under heat creating an additional pressure, but owing to the designedly large pump capacity is unable to affect the jacket pressure. This additional pressure, therefore, acts downwardly upon the surface of the downwardly flowing water, increasing the hydrostatic head to thereby increase the mass of water flowing to the pump. Thus, the volume and velocity are indirectly controlled by the vapor pressure and are not governed entirely by the pump.

One important object of the invention is to provide an improved cooling system whereby operation of internal combustion engines both of the gasoline and Deisel types may be effected at high water jacket temperatures thus giving great economy of fuel by increasing the thermic efficiency and the mean effective pressure of the engine for the pre-

vention of water oil emulsion formation on the cylinder walls, thereby decreasing piston friction and crank case dilution.

It may be mentioned that in effecting this object the ordinary gasoline engines are operated at 276 degrees Fahrenheit with perfect control while the Deisel engines are operated at 400 degrees Fahrenheit or more under vapor pressure of 200 pounds per square inch or more.

Among the other important objects of my invention are the provision of a hermetically sealed cooling system for internal combustion engines so arranged and constructed that the cooling may be effected with fresh water or volatile fluids, without loss by evaporation, and at engine water jacket temperatures above the atmospheric boiling points of such fluids; to provide an improved internal combustion engine cooling system so arranged and constructed as to increase the thermic efficiency of the engine by greatly increasing, above the usual point, the external temperature of the cylinder walls and the temperature of the combustion space, thereby decreasing heat losses by transference to the cooling medium, such losses being known to be, at low temperatures, directly proportional to the difference between the temperature in such combustion space and the fluid circulating in the water packet; to provide an improved cooling system of the class described in which cooling is effected with fluids above their atmospheric boiling points to any predetermined and desired temperature, meanwhile maintaining such fluids in a liquid condition in contact with the walls of the cylinder and combustion space; to provide an improved system of the class described wherein water, alcohol or other volatile liquids are pumped and circulated through the engine water jacket in liquid state while at temperatures greatly above their atmospheric boiling points; to provide effective cooling of the hot cylinder walls and combustion spaces directly proportional to the specific heat of the liquid circulated under all conditions of temperature; to provide an improved cooling system whereby a large portion of the heat heretofore lost to the cooling fluids and exhaust may be converted into mechanical power for use for propulsions by improved and novel means; and to establish and provide an automatic self-regulating cooling system which will maintain the engine water jackets at constant temperatures during operation regardless of the load on such engine.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation, partly in section, showing a marine motor of internal combustion type installed in a vessel with my invention applied thereto.

Figure 2 is a rear elevation thereof, partly in section.

Figure 3 is a plan view thereof.

Figure 4 is a vertical section of an automatic hydrostatic fluid control valve used herewith.

Figure 5 is a vertical section of a certain deaeration fluid check valve used herewith.

In the embodiment of my invention herein disclosed I have illustrated the same as applied to a marine engine but it is to be understood that the invention is equally applicable to any other type of internal combustion engine. In this embodiment the engine is indicated in general at 10 and is shown as mounted within the hull of a ship S. This engine is provided with the usual water jacket 15 for the cylinders and for the purpose of positively circulating the water there is provided a circulating pump 11 which has its discharge 12 connected through a manifold 13 to the water intakes of the engine cylinders. Leading from the cutlets or exhaust of these water jackets are the branches of a manifold 14 which is connected by a pipe 15 to the upper part of a vertically disposed cylindrical tank 16 closed at its top and constituting what is

preferably termed an expansion tank. In operation liquid fills the tank substantially to the water line 17 so that the upper part of the tank 16 forms a vapor chamber. It will be understood that the pump 11 may be driven from the engine by a suitable gearing 18 or may be driven in any other desired manner. On the upper end of the tank 16 there is provided an outwardly opening relief valve 19 which may be of any preferred type, opening to allow air or vapor to pass out through a discharge pipe 20 to any suitable place but closing against the admission of any air through the tank 16. From the upper part of the tank 16 is a pipe 21 provided with a stop valve 22 which leads to a condenser coil 23 contained in a vertical tank 24. The pipe 21 connects to the upper end of the condenser coil and from the lower end of said coil a pipe 25 having an outwardly opening check

valve 26 leads to a suction pump or jet device, which may be of the ordinary Venturi type, indicated at 27 in the intake 28 of the pump 11. The pump intake is extended by means of a pipe 29 to a cooling coil 30 of any suitable type, the coil being here shown as consisting of a length of pipe extending fore and aft alongside of the keel of the ship although it is to be understood that this arrangement is but typical of any cooling device cooled in any desired manner. The re-

maining end of this cooler is connected by a pipe 31 to the tank 16 of the bottom thereof so that the circulated liquid from this tank is drawn by the pump through the cooler 30, being supplied to the pump through the pipe 29 and the intake 28 thus creating suction at the suction device 27.

The tank 24 is supplied with cold water by means of a pipe 32 leading from the outboard of the ship or from any other convenient source of supply, to the upper part of said tank and from the lower part of the tank a pipe 33 leads to the suction or intake side of the pump 34 preferably mounted on the same shaft as the pump 11 though it is obvious that either or both of these pumps may be independently driven. From the outlet or delivery side of the pump 34 a pipe 35 leads to the jacket 36 of the engine exhaust manifold, the water discharging overboard from this manifold, if desired, through the pipe 37. In some cases, as those of large Diesel engines, the engine exhaust manifold will be cooled by the same cooling fluid as that used for the cylinders and combustion spaces. In such cases the proper pipe lead will be made from the pump 11 to the exhaust manifold jacket 36 and then the discharge pipe 37 will be led directly into the pipe 15 close to where it enters the tank 16. Under such cases the pipe 35 will be replaced by a suitable pipe leading directly overboard.

At 38 is indicated in general a certain hydrostatic fluid control valve which will be presently described in detail and this valve is connected by a pipe 39 with the intake 29 at a point more remote from the pump 11 than the suction device 27. Also the valve 38 is connected by a pipe 40 with a second water cooler 41 which I preferably term a super-cooler and which may be arranged around the keel similar to the coil 30 or, like it, in any preferred manner to cool the liquid passing therethrough. The remaining end of this super-cooler is connected by a pipe 42 with a special inlet valve 43 which is preferably termed a deaeration fluid check valve or aero-absence valve and a construction of which will be more specifically described hereinafter, this construction being shown in Figure 5.

At 44 is a reserve tank for the reserve supply of the cooling liquid and this tank is connected by a pipe 45 with a valve 46 within the tank 16, this valve being controlled by a float 47 so that, so long as the water level 17 is maintained at the proper point, the valve 46 will remain closed, opening only when this water level drops below the desired height. Moreover, the upper part of the tank 44 is connected by a pipe 48 with the upper part of the tank 16, the pipe 48 entering the tank and being extended downward as at 49 to a point normally slightly below the water

level 17 so that when the water level drops the pipe 48 is placed in communication with the upper part of the tank 16 and the pressure within the tanks 16 and 44 above the liquid 5 contained therein is thereby equalized so that there is no resistance to flow of liquid from the tank 44 to the tank 16 when the valve 46 is opened. This tank 44 is provided with a suitable filler cap 50 so arranged and packed 10 that it may be used to hermetically seal the tank 44 when screwed home. The described arrangement is but typical, it being contemplated that any suitable means may be utilized for maintaining the water level or refilling.

As a means of utilizing the vapor pressure at certain stages in the operation of the device, and which becomes available at those stages, I may provide a steam turbine 51 having a supply pipe 52 connected to the pipe 21 and thus to the upper part of the tank 16, the supply pipe being provided with a throttle 53. The exhaust from this turbine is led back by a pipe 54 into the condenser coil 23. 25 The power derived from the turbine may be utilized in any desired manner, as for instance by coupling the turbine shaft at 55 to a dynamo 56.

At 57 is shown a suitable dial or other 30 regulating valve or cock which is placed in the line 29 more remote from the pump 11 than the connection of the valve 38. Connected to the top of the tank 16 is a vacuum gauge 58, a pressure gauge 59 graduated in 35 pounds per square inch and a pressure gauge 60 which is graduated in degrees of temperature so that the vapor pressure of pure deaerated water may be read at the corresponding pressures on the gauge 59. Moreover, there is connected to the line 25 a gauge 40 61 which is a compound gauge graduated to show the differential existing in the condenser when pressure exists in the upper part of the tank 16 and also to show dynamic suction or lift in inches of mercury when 45 sub-atmospheric conditions exist, that is when direct static vacuum exists in the upper part of the tank 16. A thermometer 61' is also connected to the manifold 14 for showing 50 the temperature of the liquid in contact with the cylinder walls.

The fluid control valve 38 has a body 62 of the usual shape common to stop or throttle valves, this body having a seat 63. The upper 55 part of the body is, however, provided with an extended flange portion 64 threaded on its exterior, this flange portion being dished to provide a recess or chamber 65. Centrally of the body is the usual guide opening 66 for the valve stem 67 carrying on its lower end a valve proper 68 which, when closed, engages the seat 63. It is to be understood that while in the form shown in the drawings this valve is a cone valve yet other types such as those 60 employing flat rubber seats may be substitut-

ed without change in the invention. A bleeder opening 69 leads from the inlet side of the valve body to the chamber 65. Screwed onto the threaded flange 64 is a valve bonnet 70 having a centrally disposed cylindrical portion and a wider lower end so that a diaphragm 71 is held between the upper edge of the flange 64 and the valve bonnet, the bonnet being recessed at 72 to provide a chamber above this diaphragm. The stem 67 has an upwardly extending threaded portion 73 which passes through the center of the diaphragm and on this threaded portion is screwed a disc 74 which thus clamps the diaphragm between the valve stem and said disc 75 so that as the disc moves up and down at its center the valve correspondingly opens and closes. It will be noted that the disc 74 fits closely in the lower part of the valve bonnet. Screwed through the upper part of the valve bonnet is an adjusting screw 75 which bears against a disc 76 forming the seat for the upper end of a compression spring 77, the lower end of which seats on the disc 74. The adjusting screw 75 is provided with a suitable lock nut 78 and is preferably covered by a cap 79. By this means it will be seen that downward pressure on the diaphragm may be regulated so that the valve will only open when pressure in the chamber 65 resulting from pressure on the inlet side of the valve being transmitted through the opening 69, becomes sufficient to raise the valve against the action of the springs. Moreover, the valve will only lift off its seat to just such extent that the fluid passing through the valve will equalize the pressure in the chamber 65 with the pressure produced by the compression of the spring 77. The valve thus, when set for a given pressure on the outlet 105 side automatically maintains that pressure. The valve 38 is also of special construction. This valve has a body 80 of the ordinary form, the body having an upwardly extending neck 81 closed by a cap or bonnet 82. 110 Also the body has a downwardly extending neck 83 having a segmento-spherical flange 84 projecting from its lower end and terminating outwardly in a flat peripheral flange 85. This portion of the body forms 115 the top of the diaphragm housing the lower portion of which has its central part 86 shaped similarly to the part 84 and is provided with a flange 87 corresponding to the flange 85 so that the two parts of the housing 120 may be held together by bolts 88. In the valve body 80 is the usual seat 89 whereon seats a valve proper 90 and in the partition between the inlet and outlet ends of this valve is a bleeder opening 91 which thus opens beneath the valve 90. The valve 90 is provided with a stem 92 having a spider 93 on its upper end which fits within the neck 81 to guide the valve. Similarly the lower part of the stem is provided with a fluid packed piston 130

head 94 which fits closely within the cylindrical bore of the neck 83. The diaphragm consists of two yieldable plates having segmental spherical central portions 95 and flat peripheral portions 96 secured together by rivets or bolts 97, the edges of these plates being held between suitably spaced portions of the peripheral flanges 85. By this means the diaphragm constitutes an ellipsoidal cell.

10 In operation this diaphragm is partly filled with water and for the proportions of this invention it is preferred that the water should be 60 degrees Fahrenheit when it is placed in the diaphragm and that the air shall be 15 at 760 millimeters atmospheric pressure as measured by a mercury column. Under any conditions there will always be provided just sufficient water to insure a saturated mixture of air and water vapor at whatever predetermined maximum temperature and the above barometric pressure the valve will be in neutral position, neither expanded nor contracted. If the temperature is lowered the 20 aqueous vapor pressure in the cell is decreased, as is also the volume of air, and the cell will contract. Likewise, increasing the temperature causes increase of aqueous vapor and air pressure in the cell so that the cell will expand. Centrally of the diaphragm 25 housing 86 is a boss 97 and threaded through this boss is an adjusting screw 98 provided with a nut lock 99. The inner end of this screw engages a pressure thrust block 100 secured centrally to the lower side of the cell 30 by means of a suitable nut 101. On top of the cell is mounted a diaphragm thrust block 102 which is secured to the cell by a suitable bolt 103. This thrust block 102 is positioned so that normally it is spaced a few thousandths of an inch below the lower surface of the piston head 94. This piston head is preferably made hollow and provided with a bleeder opening 104 so that pressure above and below the head is equalized, it being observed 40 that the bleeder 91 also equalizes pressure above and below the valve 90. It is intended that the cell shall expand upwardly at all times and to this end the lower side of the cell is supported on annular ribs or supports 105, the central portion being obviously supported on the screw 98. In order to understand the operation of the remainder of the device it is advisable here to consider the operation of this particular valve as much 45 as depends thereon and it will be noted that the upper diaphragm casing 84 is provided with suitable openings 106 so that the contents of the tank in which the valve is placed may flow in and surround the cell.

50 For the purpose of understanding the operation of this valve it may be mentioned that at the start of the operation of the cooling system the tank 16 will be filled to the water line 17 with water containing a certain amount of air in solution while above the

water the tank will be filled with air which naturally contains a certain amount of aqueous vapor. Now, since the water in the tank surrounds the cell the temperature of the water in the cell will be the same as the temperature of the water in the tank and, assuming that when the tank is filled and closed the atmospheric pressure in the upper part is 760 millimeters of mercury, the vapor tension in the upper part of the cell will be identical with the vapor tension in the upper part of the tank thus a state of equilibrium exists and no movement of the valve 90 will take place. Under operation of the system the water from the tank 16 is circulated 75 through the water jackets of the engine and accordingly becomes hot so that the vapor pressure above the water in the tank increases. As an example we may say that the valve 19 had been set to open at 210 pounds per square inch. When, therefore, the vapor pressure in the upper part of the tank equals 80 210 pounds the valve 19 will open and the air will escape during the blow down from the tank. Now, remembering that when the water has been heated to bring the pressure above the water line to 210 pounds the water in the cell has also been heated and the cell pressure has likewise been raised to 210 pounds. Upon opening of the valve 19 air 85 will escape during the blow down which thus decreases the pressure above the water line while at the same time the cell, being hermetically sealed does not have its pressure decreased and will expand upwardly so that the valve 90 will be forced off its seat, this 90 will allow escape of some of the hot water from the tank 16, lower the water level and open the valve 46 for the admission of cold water from the tank 44 so that the water in 100 16 is cooled, the cell contracts, the valve 90 seats and the water again rises to its normal level. Now, since what escaped through the valve 19 was principally air with a small amount of water in the form of vapor, repetition of this operation will finally free all of the water in the circulating system from air 105 gas until eventually the tank 16 will be filled to the water line with water and above the water line with aqueous vapor free from air, it being remembered that the air in solution in the water is given off at a temperature much below its boiling point. However, air will always remain in the cell so that no matter what the temperature of the water in the tank 16 may be or what may be the variation in the pressure it will always be less than that within the cell thus the valve will be normally held off its seat until by accidental leakage or intentional admission of air into the tank the combined vapor and air pressure above the water line becomes equal to that within the cell. However, as will be presently understood the water line under these 110 circumstances will not drop below its nor 115 120 125 130

mal point so that the valve 46 will normally remain closed. It is further to be understood that wherever water is mentioned here any other suitable circulating liquid such as an anti-freeze mixture of alcohol is intended to be understood.

I will now describe the complete operation of the system. Assuming that the condition is that the engine is cold and not running and that the tank 16 contains air and aqueous vapor in its upper part as previously described then the valve 43 will be closed. If the engine be now started the pumps 11 and 34 also start to operate or may be started if separately driven, the pump 34 when thus started operates to circulate cold water through the condenser 24 around the coil 23. At the same time the pump 11 forces water through the engine water jackets and their connections into the upper part of the tank 16. The water which is thus forced through the water jackets is drawn through the pipe 29 from the cooler 30 and as it passes the suction device 27 exerts a powerful suction on the pipe 25. Just at the start the water level 17 will drop slightly but due to the suction exerted on the pipe 27 the vapor above the water level with a certain amount of air will be drawn through the pipe 21 and coil 23, the vapor being there condensed. Thus an emulsion of air and water will first be circulated through the water jacket to the engine and since this emulsion of air and water has a specific heat much less than that of water itself the engine will quickly heat up so that the water in the tank 16 will quickly become hot and the pressure in such tank will increase. Consequently, when the pressure has reached the desired point, the valve 19 will open and a certain amount of air and vapor will pass out, it being remembered that the remainder will always be drawn through the condenser and be condensed, the water escaping being replaced in the tank 44 as previously described. This operation will continue automatically until the circulating water has been freed from air. As before noted when this takes place the valve 43 will remain constantly open and the valve 46 constantly closed. Now, since the valve 19 is set to blow off at such pressure as corresponds with the desired temperature to be maintained in the cylinder jackets and since the condenser will condense all of the vapor passing through it, its size being proportioned to effect this object, there will cease to be an emulsion of air and water circulating through the water jackets but the circulating medium will then be water which, with its relatively high specific heat, will prevent the cylinder walls and combustion chamber of the engine from rising above the desired temperature. The cylinder walls and combustion chamber are thus permitted

quickly to attain the desired temperature and then maintained at that temperature.

The valve 57, which as stated is a suitable dial controlling valve, is placed in the main suction line of the pump 11 and the cooling fluid circulates through it in normal engine operation. By reference to the dial of the valve, such valve can be accurately adjusted to throttle the mass flow to the pump, so that only the approximately necessary volume of water will be pumped per minute to maintain the engine jacket water, say, at 380° Fahrenheit. At 380° Fahrenheit, the aqueous vapor pressure is 196 pounds per square inch. If the temperature in the engine jacket under any condition of operation starts to increase and rises, say, to 382° Fahrenheit, the steam pressure in the system will increase to substantially 200 pounds per square inch. Under these conditions, the valve 38, which has been set for this predetermined pressure, will open and admit into the pump suction, in advance of the valve 57, a stream of cold water through the pipe 40 from the super-cooler 41, of a volume equal to the pump's unrestricted suction capacity. This volume of cold water, entering the engine jacket, quickly reduces the temperature therein and the consequent drop of pressure when the temperature reaches a point slightly below 382° Fahrenheit, say 377° Fahrenheit, at which the pressure of the aqueous vapor is approximately 190 pounds per square inch, will permit the valve 38 to close. Thus, cooling from the increased mass flow of cool water is automatically cut off. The cooling medium is thus under perfect control, the pump being by design of a capacity and discharge so greatly in excess of the normal operating conditions that its discharge is not effected by the back pressure in the jacket. The mass flow is automatically controlled by the volume of cooling water admitted to the suction and is dependent upon and the volume entering the engine jacket is controlled according to the increase or decrease in the engine temperature.

Therefore, as the valve 19 is set for a definite pressure corresponding to a definite temperature of aqueous vapor, this valve cannot again open because the valve 38, which is set for opening at a pressure less than that of the valve 19, will, as stated, permit an entrance of cool water into the system to reduce the temperature of the cooling medium and thereby the pressure of the aqueous vapor, before such pressure reaches the point at which valve 19 opens. Therefore, when working with the water deaerated, the predetermined working temperature and pressure cannot be exceeded nor can valve 19 again open, for without air in the system to close the aero-absence valve 43, such valve 43 will always remain open and as the temperature will be always controlled and reduced when reaching

the predetermined limit by the injection of cold water into the jacket, any material rise of aqueous vapor pressure is absolutely prevented.

5 Having thus described the invention, what is claimed as new, is:

1. In a cooling system for internal combustion engines, a circulatory system for the cooling fluid permanently closed against the admission of air, means for relieving the system of the initially contained air under a predetermined pressure of such contained air, and means for continually redelivering the contained air to the cooling medium up to the 15 point of said predetermined pressure.

2. In a cooling system for internal combustion engines, a circulatory system for the cooling fluid permanently closed against the admission of air, means for relieving the system of the initially contained air under a predetermined pressure of such contained air, and means for continually redelivering the contained air to the cooling medium up to the point of said predetermined pressure, said 25 latter means being governed by the circulation of the cooling medium.

3. A water cooling system for internal combustion engines, comprising a circulatory system for the cooling medium including a pump 30 and a reservoir providing a vapor chamber above the circulating medium, a circulation controlling valve governing an additional communication to the pump and arranged in the reservoir, said valve being responsive to 35 the pressure variations governed by the heat of the water in the reservoir.

4. A water cooling system for internal combustion engines, comprising a circulatory system for the cooling medium including a 40 pump and a reservoir providing a vapor chamber above the circulating medium, a circulation controlling valve governing an additional communication to the pump and arranged in the reservoir, said valve being responsive to the pressure variations governed by the heat of the water in the reservoir, and means for cooling the circulating medium.

5. In a water cooling system for internal 50 combustion engines, a circulatory system for the cooling fluid including a pump and a reservoir providing a vapor chamber above the level of the cooling medium within the reservoir, and means controlled by the heat conditions of the cooling medium of the reservoir for relieving the reservoir under predetermined heat conditions of a portion of the heated cooling medium.

6. In a water cooling system for internal 60 combustion engines, a circulatory system for the cooling fluid including a pump and a reservoir providing a vapor chamber above the level of the cooling medium within the reservoir, means controlled by the heat conditions of the cooling medium of the reservoir

for relieving the reservoir under predetermined heat conditions of a portion of the heated cooling medium, and means for delivering such portion of the heated cooling medium from the reservoir to the suction side of the pump.

7. In a water cooling system for internal combustion engines, a circulating system for the cooling fluid including a pump and a reservoir providing a vapor chamber above the level of the cooling medium within the reservoir, means controlled by the heat conditions of the cooling medium of the reservoir for relieving the reservoir under predetermined heat conditions of a portion of the heated cooling medium, means for delivering such portion of the heated cooling medium from the reservoir to the suction side of the pump, and a hydrostatic valve for controlling such delivery.

8. In a water cooling system for internal combustion engines, a circulating system for the cooling fluid including a pump and a reservoir providing a vapor chamber above the level of the cooling medium within the reservoir, means controlled by the heat conditions of the cooling medium of the reservoir for relieving the reservoir under predetermined heat conditions of a portion of the heated cooling medium, means for delivering such portion of the heated cooling medium from the reservoir to the suction side of the pump, and means for cooling such portion of the cooling medium prior to its delivery to the pump.

9. A cooling system for internal combustion engines, including a circulatory system for the cooling medium having a pump and a reservoir, with the latter providing a vapor space above the level of the cooling medium therein, a second circulatory path between the reservoir and suction side of the pump, a valve normally closing said second circulatory path, and means for controlling the valve, said means being responsive to the heat conditions of the cooling medium in the reservoir.

10. A cooling system for internal combustion engines, including a circulatory system for the cooling medium having a pump and a reservoir, with the latter providing a vapor space above the level of the cooling medium therein, a second circulatory path between the reservoir and suction side of the pump, a cooling means for said second circulatory path, a valve normally closing said second circulatory path, and means for controlling the valve, said means being responsive to the heat conditions of the cooling medium in the reservoir.

11. A cooling system for internal combustion engines, including a circulatory system for the cooling medium having a pump and a reservoir, with the latter providing a vapor space above the level of the cooling medium

therein, a second circulatory path between the reservoir and suction side of the pump, a cooling means for said second circulatory path, a valve normally closing said second circulatory path, means for controlling the valve, said means being responsive to the heat conditions of the cooling medium in the reservoir, and means in said second circulatory path controlled by the pressure of the vapor in 10 said vapor chamber for governing the quantity of cooling medium delivered to the suction side of the pump through such second circulatory path.

12. A cooling system for internal combustion engines, including a circulatory system for the cooling medium having a pump and a reservoir, with the latter providing a vapor space above the level of the cooling medium therein, a second circulatory path between the 15 reservoir and suction side of the pump, a cooling means for said second circulatory path, a valve normally closing said second circulatory path, means for controlling the valve, said means being responsive to the heat conditions of the cooling medium in the reservoir, means in said second circulatory path controlled by the pressure of the vapor in said vapor chamber for governing the quantity of 20 cooling medium delivered to the suction side of the pump through such second circulatory path, and means controlled by the level of cooling fluid in the reservoir for governing admission of additional cooling fluid to the 25 reservoir.

30 13. A cooling system for internal combustion engines, including a circulatory system permanently closed against the admission of air, means to circulate the contained air from the cooling medium, means to permit systematic ejection of the contained air at predetermined temperatures of operation, and means to thereafter automatically maintain 35 the system free from air.

40 14. In a cooling system for internal combustion engines, a circulatory system for the cooling fluid permanently closed against the admission of air, means for relieving the system of initially contained air under a predetermined pressure of such contained air, and 45 means for automatically introducing into the system an additional volume of cooling medium when the temperature of the cooling medium in the system reaches a predetermined point.

50 15. In a cooling system for internal combustion engines, a circulatory system for the cooling fluid permanently closed against the admission of air, means set for operation at a predetermined pressure for relieving the 55 system of the initially contained air, and means set for operation at a somewhat lower pressure for admitting into the system an additional supply of cooling medium.

60 16. In a water cooling system for internal combustion engines, a circulatory system for

the cooling fluid including a pump, a reservoir providing a vapor chamber above the level of the cooling medium within the reservoir, a relief valve for the vapor chamber set to open at a predetermined pressure, a hydrostatic valve for admitting an additional volume of cooling medium to the pump, said hydrostatic valve being set to open at a pressure less than the setting of the relief valve, and means controlled by the heat conditions 70 of the cooling medium in the reservoir for delivering cooling medium through the hydrostatic valve, said means being closed under pressure conditions in the vapor chamber tending to effect an opening of the relief 75 valve.

In testimony whereof I affix my signature.
CLINTON ROOT FOUTZ.
